DESIGN FOR A CASE FOR A COMBINED BATTERY TESTER AND CHARGER

Merlin L. Pugh, Minneapolis, Minn., assignor to Guy L. Pugh, Minneapolis, Minn.

Application October 17, 1938, Serial No. 80,495

Term of patent 7 years

To all whom it may concern:

Be it known that I, Merlin L. Pugh, a citizen of the United States, residing at Minneapolis, in the county of Hennepin and State of Minnesota, have invented a new, original, and ornamental Design for a Case for a Combined Battery Tester and Charger, of which the following is a specification, reference being had to the accompanying drawing, forming part thereof.

Fig. 1 is a perspective view from the front of a case for a combined battery tester and charger showing my new design.

Fig. 2 is a plan view of the top panel shown in Fig. 1.

I claim:

The ornamental design for a case for a combined battery tester and charger, as shown.

MERLIN L. PUGH.
